(57) **CLAIM**

The ornamental design for a utensil, as shown and described.

DESCRIPTION

FIG. 1 is a perspective view of a utensil in accordance with the present design in a closed configuration;

FIG. 2 is a rear elevation view thereof;

FIG. 3 is a front elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the present design in an open configuration.

The broken lines shown in the drawings illustrate portions of the utensil that form no part of the claimed design.

1 Claim, 5 Drawing Sheets
